US00D661206S

(12) **United States Design Patent**
Register et al.

(10) **Patent No.:** **US D661,206 S**
(45) **Date of Patent:** ** Jun. 5, 2012

(54) **ELECTRONIC DEVICE**

(75) Inventors: **Todd P. Register**, Olathe, KS (US);
Jonathan R. Hosler, Overland Park, KS
(US)

(73) Assignee: **Garmin Switzerland GmbH** (CH)

(**) Term: **14 Years**

(21) Appl. No.: **29/389,061**

(22) Filed: **Apr. 6, 2011**

(51) LOC (9) Cl. **10-02**

(52) U.S. Cl. **D10/38**

(58) **Field of Classification Search** D10/30-39,
D10/122-132, 97; 368/276, 281, 282; D14/344;
D24/167

See application file for complete search history.

(57) **CLAIM**

The ornamental design for an electronic device, as shown and described.

DESCRIPTION

FIG. 1 is a front perspective view of an electronic device showing our new design;

FIG. 2 is a rear perspective view of the electronic device;

FIG. 3 is a front view of the electronic device;

FIG. 4 is a rear view of the electronic device;

FIG. 5 is a top view of the electronic device;

FIG. 6 is a bottom view of the electronic device;

FIG. 7 is a left side view of the electronic device; and,

FIG. 8 is a right side view of the electronic device.

Portions of FIGS. 1 through 8 are shown in dashed lines for illustrative purposes only and form no part of the claimed design.

1 Claim, 4 Drawing Sheets
